UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed July 22, 1926. Serial No. 124,160.

The present invention relates to controllers for refrigerating systems, and particularly to controllers for affecting the degree of refrigeration.

In practice of mechanical refrigeration, it is necessary that some apparatus be operated at a relatively lower average temperature than other apparatus. For example, it is desirable to maintain the average temperature of the cabinet of a household refrigerating apparatus at approximately 45° F., while in other refrigerating apparatus, such as used with ice-cream cabinets, it is necessary to maintain an average temperature considerably below freezing point. In either system it is desirable to provide a relatively fine adjustment of a controller, whereby to start and stop the refrigerating cycle at any desired temperatures within certain limits. To facilitate the economical manufacture of refrigerating systems, it is desirable to utilize one controller which is adaptable to different apparatus. One of the objects of the present invention is to provide a controller which can be adapted for use with different refrigerating apparatus which operate to produce refrigeration at different average temperatures, said controller being provided with means for securing a relatively fine adjustment when the controller is utilized with any apparatus.

Further objects and advantages of the present invention will be apparent from the following description, reference being had to the accompanying drawings, wherein a preferred form of the present invention is clearly shown.

In the drawings:

Fig. 1 is a partly-sectional and partly-elevational view of a controller;

Fig. 2 is a fragmentary sectional view of a portion of said controller, showing certain elements in one position; and

Fig. 3 is a view similar to Fig. 2, but showing elements in a different position.

Referring to the drawings, there is shown a platform 20, to one end of which there is secured a metal bellows 21 which is connected with a tube 22. Tube 22 is preferably connected on the low-pressure side of the refrigerating

system and, therefore, adapted to contain a refrigerant, and is likewise responsive to the pressure within said low-pressure side.

A frame 24 is carried by the platform 20 and is provided with ears, one of which is shown at 25. An operating member 26 is pivotally mounted at 27 upon the ears 25. Lever 26 is pivotally connected at 28 with ears, one of which is shown at 29, carried by the top wall 30 of bellows 21. It is apparent that lever 26 will be rotated about pivot 27, in response to the pressure within the bellows 21.

A yoke 32 is carried on the other end of platform 20 and the head 33 of lever 26 extends between the legs of said yoke. A bushing 34 is secured to the top wall of yoke 32 by a nut 35. A plunger 37 extends through the bushing 34, and is disposed in the path of movement of head 33 of lever 26. Plunger 37 is provided with an enlarged portion 38 adapted to limit the downward movement of said plunger and adapted to provide a shoulder for coil springs 39 and 40, which are disposed within the bushing 34. The exterior portion of the bushing 34 is screw-threaded and is adapted to be received by an adjusting nut 42 adapted to be locked in position by a locknut 43. A washer 44 is located within the nut 42, and springs 39 and 40 are adapted to be interposed between said washer 44 and the shoulder 38. Washer 44 prevents twisting of the springs while the device is being adjusted but it is not essential. In Fig. 2, spring 39 only is shown effective; and in Fig. 3 the nut 42 has been moved to a position in which both springs 39 and 40 are effective. Springs 39 and 40 are wound oppositely to one another, so as to prevent the coils of spring 40 from moving into the spaces between the coils of spring 39.

An examination of the drawings will disclose the simplicity of the controller. The members 34 and 42 provide both a casing and an adjusting means. The reverse position of the springs 39 and 40 also aids in preserving the adjustment disclosed in Fig. 3. As the member 42 is screwed down, the force of compression travels clockwise, looking down, through the clockwise wound coils of the spring 39. Accordingly the reaction of the

100

- spring 39 against this compression is in an anti-clockwise direction against the compressing member. As the adjacent spring 40 is oppositely wound in a counter clockwise direction, its reaction is in a clockwise direction to the force of compression. Accordingly these two reactions being opposite to one another will tend to neutralize each other and will not tend to disturb the adjustment.
- 10 If both springs were wound the same way, the reaction of both of them against the member 44 or the member 42 if the member 44 were not used might tend to exert a couple that would tend to loosen the adjustment in case 15 the apparatus is jarred or vibrated frequently. Thus the oppositely wound adjacent springs tend to maintain the adjustment.
- The underside of platform 20 carries a contact block 45, upon which there is mounted 20 a stationary contact 46 and a movable contact 47 pivotally mounted at 48, which contacts are connected, respectively, with conductors 49 and 50. A lever 52 is pivotally mounted at 25 53 upon the lever 26 and a link 54 is pivotally connected with lever 52 by a pin 55. Link 54 is also pivotally connected with movable contact 47. The opposite end of lever 52 is provided with camming surfaces 56 and 57, which are arranged to cooperate with a roller 30 59 carried by a roller bracket 60 which is pivotally mounted at 61 upon the legs of yoke 32. A spring 62 is wound around the pivot 61 and the ends thereof engage a pin 63 and the bracket 60, whereby said spring normally 35 tends to move the roller bracket 60 and, likewise, the roller 59 to the right, as viewed in Fig. 1. When the spring-pressed roller 59 cooperates with the camming surface 56, it normally tends to maintain the lever 52 in the 40 position shown in Fig. 1. However, when said roller engages camming surface 57, it maintains the lever 52 in such position that contact 47 engages contact 46.
- When the pressure within the bellows increases, the lever 26 is moved upwardly, 45 thereby causing the lever 52 to be moved upwardly. A stop 64, carried by the pivotally-mounted contact 47, engages the top wall of block 45 and limits the counterclockwise 50 movement of contact 47 and, likewise, limits the upward movement of the right-hand end of lever 52. Therefore, on the upward movement of lever 26, lever 52 will fulcrum about pin 55 and the camming surface 56 will be 55 moved over the roller 59, and when the lever 52 has moved beyond the dead center position, formed by the camming surfaces 56 and 57, the roller will cooperate with camming surfaces 57 to quickly rotate the lever 52 about pivot 53 and cause contact 47 to engage contact 46. Since the plunger 37 lies within the 60 path of movement of head 33 of lever 26, the aforementioned upward movement of lever 52 is resisted by the spring 39, or, if both 65 springs are operative, by springs 39 and 40.

When the pressure within the bellows decreases, the lever 26 will move downwardly. It will be observed that, while contact 47 is in its engaging position with respect to contact 46, lever 52 will be disposed at an angle 70 inclining upwardly from the right to the left. Therefore, pivot 53 must be moved to a lower position when lever 26 is moving downwardly, before the dead center position of surfaces 56 and 57 are reached, than when the lever 26 is moving upwardly. The construction of the mechanism is such that the head 33 will move away from the plunger 37 before the lever 52 is moved beyond the dead center position, the enlarged portion on shoulder 38 limiting the downward movement of plunger 37. Therefore, the springs are rendered ineffective and the pressure, at which the contacts are separated, is controlled by either of the adjustable tension springs 65. 80 or 66.

When the controller is utilized in a refrigerating system for cooling ice-cream cabinets or the like in which a relatively low temperature is desired, the nut 42 is substantially in 90 the position shown in Fig. 2, in which position spring 40 is not utilized; and the nut 42 being adjustable with respect to the bushing 34, permits the regulation of the tension of spring 39, whereby to control the resistance 95 of said spring. Thus it is apparent that since spring 39 is longer than spring 40, a relatively wide range of adjustment may be had without bringing the spring 40 into operation. However, if it is desirable to utilize the present controller for an apparatus for cooling 100 the household refrigerator cabinet, or the like, in which a relatively higher temperature is desirable, the nut 42 is moved to substantially the position shown in Fig. 3, in which 105 position the spring 40 augments the resistance offered by the spring 39. The springs 39 and 40 may be more or less compressed by the nut 42 to thus vary the resistance offered 110 to the upward movement of lever 26.

It is apparent from the foregoing that a controller has been provided which may be accurately adjusted to respond to slight pressures within a certain pressure range and which may be accurately adjusted to respond 115 to relatively different pressure ranges.

It is also apparent that by virtue of the disclosed spring arrangement, there has been provided a controller in which certain elements thereof may be made compact while at 120 the same time maintaining sufficient flexibility for accurate adjustment, for the purpose heretofore specified. The springs 39 and 40 provide a resistance device having variable resistance characteristics. When only one spring is utilized, the resistance offered thereby has a different resistant characteristic than when both are utilized. By providing a resistance device having variable resistance characteristics, a relatively fine adjustment 125

may be had when operating within a certain range of pressure and when operating within a relatively different range. By providing two superimposed springs of different lengths, short springs can be used thus obtaining compactness while still maintaining relatively fine adjustments as described.

The present invention has been described as applied to the low-pressure side of a refrigerating system. It is to be understood, however, that the control may be responsive to different sources of pressures.

While the form of embodiment of the invention as herein disclosed constitutes a preferred form, it is to be understood that other forms might be adopted, all coming within the scope of the claims which follow.

What is claimed is as follows:

1. A controller for a refrigerating system comprising in combination an operating member responsive to conditions in the system, and a resistance member for said operating member comprising an adjustable casing, a plurality of spring members inside the casing adapted to resist the movement of said operating member in one direction, the adjustment of said casing determining the number of spring members made operative.

2. A controller for a refrigerating system comprising in combination an operating member responsive to conditions in the system, and a resistance member for said operating member comprising an adjustable casing, a shaft passing axially through said casing and positioned to bear against said operating member, an enlarged portion on said shaft within said casing, a plurality of spring members within said casing adapted to exert pressure against said enlarged portion and thus resist movement of the shaft in one direction by the operating member, the adjustment of said casing determining the number of spring members made operative.

3. A controller for a refrigerating system comprising in combination an operating member responsive to conditions in the system, and a resistance member for said operating member comprising an adjustable casing including an outside screw-threaded member and an inside screw-threaded member adapted to be screwed over said outside screw-threaded member to form the casing, spring members inside said casing adapted to resist movement of said operating member in one direction, the adjustment of said inside screw-threaded member determining the number of spring members made operative to resist movement of said operating member.

4. A controller for a refrigerating system comprising in combination an operating member responsive to conditions in the system, and a resistance member for said operating member comprising an adjustable casing comprising an outside screw-threaded mem-

ber and an inside screw-threaded member adapted to be screwed over said outside screw-threaded member to form the casing, a shaft passing axially through said casing and positioned to bear against said operating member, an enlarged portion on said shaft within said casing, spring members bearing against said enlarged portion, the adjustment of said screw-threaded members upon each other determining the number of spring members made operative to oppose movement of said shaft.

In testimony whereof I hereto affix my signature.
